METHOD OF MAKING AND PREMOLDING
HEEL AND QUARTER SECTIONS OF BOOTS
AND SHOESBenjamin F. Hartwell, Leslie L. Hartwell, Jr.,
and Arthur F. Hartwell, Bellows Falls, Vt.

Application June 1, 1938, Serial No. 211,146

1 Claim. (Cl. 12—146)

Our present invention is directed to simplify the preparation of boots and shoes, particularly the heel and quarter sections, of our prior and copending application Ser. No. 146,217, filed June 5, 1937 now Patent No. 2,170,599, dated August 22, 1939; and is an improvement of our invention on process of making boots and shoes by premolding certain parts of same as described in our copending application Ser. No. 104,196, filed Oct. 10, 1936, and Ser. No. 137,708, filed April 19, 1937. As explained in our said prior application 146,217, we prepare a series or set of heel and quarter blanks while flat, folding the edge portion of the upper material over the edge of the intermediate layer or stiffening material to give a finished folded edge, and thereupon uniting the same also while flat by suitable pressure and adhesive with the lining layer, subsequently stitching and trimming the surplus lining, and then 20 premolding the entire series of united blanks into finished form with a lasted flange on the bottom portion.

In our present invention we have discovered that we can secure a substantially equivalent finished folded edge while saving the operation of first uniting the stiffening layer and outer finishing material and folding the edge of the latter over the stiffening layer and then uniting the lining.

By our present simplified process we cut the blank of the outer finished leather and then fold its edge upon itself, uniting the same with adhesive; and in this form we prepare the intermediate stiffening layer of substantially less area but similar contour along the top portion to that of the outside or finishing upper material, approximately to fit the stiffening layer just under the folded edge. Thereupon the lining is applied and all three layers are united by adhesive, and thereafter the stitching is put in, the lining trimmed, all while flat, and the three-layered blank premolded.

This present invention saves considerable handling, work, and some material on the intermediate stiffening layer while facilitating the premolding operation.

Referring to the drawing illustrating a preferred embodiment of the invention,

Fig. 1 is a plan view partly in cross-section;

Fig. 2 is a longitudinal cross-sectional view;

Fig. 3 illustrates the process of applying the stitching and trimming the surplus lining material, with a part of same broken away;

Fig. 4 is a perspective view of the finished and

premolded heel and quarter portion of a shoe on a smaller scale, and

Fig. 5 is a cross-sectional view on the same scale as Figs. 1, 2, and 3.

Referring to the drawing, 1 designates the cut- or dried-out blank of outer or finishing material for the shoe upper. 2 indicates the intermediate stiffening layer having a bevelled edge 3 also cut or died out of similar contour to that of the blank 1 but of less area to permit the folding of 10 the edge portion of the blank 1 around the top into the finished and folded edge 5. The lining 4 is of slightly greater area, and after the upper 1 has been subjected to the folding operation these 15 three layers are then united by adhesive, all while flat, and preferably by coating each surface of the inner or stiffening material with adhesive or by coating the contacting faces of the folded upper or lining, or both, and thereupon assembling the same in alignment with the top surface of 20 the stiffening layer substantially registering with the inner folded edge 5 of the upper and with the lining overlapping the same, notch marks 6 and 7 facilitating this operation, and the layers are then subjected to pressure until all are united. 25

Thereupon as shown in Fig. 3, the stitching 10 is applied around the marginal edge of the folded outer material 1, as indicated at 5, and the lining 4 as best shown in Fig. 5. During the setting of the stitching the surplus material 12 of the lining 30 is cut so that the triple layered blank is complete, with the finished edge 5 formed as a folded edge of the outer finishing material alone, the stiffening layer 2 substantially registering with the inner edge of the folded edge 5, as shown; and 35 the three-layered blank then being subjected to the premolding operation in finished form and contour with the lasting flange 15 thereon, ready for attachment to the insole or assembly with the insole on a last to complete the shoe. 40

In this form of our invention we have obtained the benefit of a folded edge by an extremely simple operation of folding the upper material onto itself without first assembling the stiffening layer and then subjecting the blank to the folding operation, thus greatly simplifying the handling and a saving in expense. 45

As formerly made and described in our said copending application 146,217, it was first necessary to assemble the stiffening layer and outer finishing material, uniting them with adhesive and pressure, and thereupon taking the two blanks thus formed to a folding machine for the folding operation. 50

By our present improved and simplified method 55

the outer layer 1 is folded immediately after it is died or cut, and thereupon all three blanks are operated upon simultaneously in the adhesive coating and uniting operations, eliminating the delay, handling, and expense incident to uniting two layers and taking them to a separate machine operation, and then returning to the operation of uniting a third or lining blank.

Consequently, the saving by our present invention in handling, time, interruption of blank-uniting processes by transporting and running thru a folding machine, together with the danger of damaging and marring the entire blank material, because the adhesive operation is extremely difficult without getting the adhesive on the outer and lining layers, are most important improvements in this particular art, and we wish to claim the same herein broadly.

We claim:

20 The improved method of preparing heel and quarter blanks for use in premolding during the

manufacture of boots and shoes, which consists in cutting out an outer finished layer from flat sheet material folding the upper edge portion of same while flat, thereupon preparing an intermediate stiffening layer of substantially less contour and area than that of the now folded edge layer to permit the stiffening layer to register while flat with the folded edge of the outer layer, preparing a lining layer of greater area than the edge folded layer, uniting said three layers by 10 adhesive, and thereafter applying stitching around the folded edge from the outer layer to the lining, and cutting off the surplus edge portion of the lining and thereupon premolding the three layers of the blank into finished heel and 15 quarter form with a lasting flange independently of assembling on a last.
